UNITED STATES PATENT OFFICE.

BENJAMIN W. TUCKER, OF SOUTH ORANGE, NEW JERSEY, AND LOUIS J. DIRAND, OF NEW YORK, N. Y., ASSIGNEES, BY MESNE ASSIGNMENTS, TO CORONA TYPEWRITER COMPANY, INCORPORATED, A CORPORATION OF NEW YORK.

TYPE-WRITING MACHINE.

1,245,535.

Specification of Letters Patent.

Patented Nov. 6, 1917.

Application filed February 21, 1914. Serial No. 820,206.

To all whom it may concern:

Be it known that we, BENJAMIN W. TUCKER and LOUIS J. DIRAND, citizens of the United States, and residents of South Orange, county of Essex, and State of New Jersey, and of New York, county and State of New York, respectively, have invented certain new and useful Improvements in Type-Writing Machines, of which the following is a full, clear, and exact description.

This invention relates more particularly to foldable visible or front strike typewriting machines.

One of the principal objects of the invention is to provide a machine having a standard or universal keyboard which is mounted on a member of the machine frame, and which is adapted to fold upward and rearward toward the platen carriage in order that the machine may be made more compact when not in use to adapt the same for convenient transportation and for other purposes.

Another object of the invention is to provide a machine in which each key of the keyboard for printing purposes is adapted to operate an independent type-bar, and which keyboard includes the spacing bar and platen shift key or keys.

Other objects of the invention are to provide means whereby the type-bars, ribbon and escapement mechanisms are out of cooperative relation with the keys when the latter are moved to a compact position, and to provide a construction wherein the delicate parts of the machine are protected against accidental operation when the parts are in a folded or compact position.

A further object of the invention is to provide a machine which while foldable has the appearance of the usual visible typewriting machine.

A still further object of the invention is to provide a machine which comprises comparatively few parts and which is adapted for general office use as well as for the use of travelers and those requiring a portable machine in which lightness and compactness is a desirable element.

With these and other objects in view, the invention will be hereinafter more particularly described with reference to the accompanying drawings, which form a part of this specification, and will then be pointed

out in the claims at the end of the description.

In the drawings, Figure 1 is a plan view, partly broken away, of one form of machine embodying the invention, showing the parts in normal operative position.

Fig. 2 is a side elevation.

Fig. 3 is a side elevation showing the parts in a folded position and of a form wherein the keyboard is adapted to be moved into overhanging relation to the platen carriage.

Figs. 4, 5 and 6 are detail views of the several printing key actions.

Fig. 7 is a detail view of the spacing key action.

Fig. 8 is a vertical section taken on the line VIII—VIII of Fig. 4.

Figs. 9 and 10 are detail views, partly in section, of a part of the platen shift mechanism.

Fig. 11 is a horizontal section of one part of the key action.

Fig. 12 is a fragmentary side elevation; and Fig. 13 is an end section of the part shown in Figs. 11 and 12.

Figs. 14 to 16 are views similar to Figs. 11 to 13 except that a slightly different form of key action construction is shown.

Figs. 17 to 19 are views similar to Figs. 11 to 16 except that a slightly different form of breakable key action connection is shown.

Fig. 20 is a side elevation of a machine somewhat like that already described, except that the type-bars are operated by a pull action instead of a pushing action as in the other figures.

Figs. 21 to 23 are detail views of the key actions of the printing characters.

Fig. 24 is a detail view of the spacing key action; and

Figs. 25 and 26 are detail views of a part of the platen shift mechanism.

The frame of the machine comprises a main member 10 and a foldable member 11. The main member 10 is adapted to support the main mechanism of the machine and the member 11 is adapted to support the keyboard or that portion which contains the operating finger keys. The main member 10 as well as the member 11 may be made of sheet steel, aluminum, or any other material and may be of such a character as to be light and strong. As shown the member 10 comprises side plates or members 12 and

a rear plate or member 13. The member 10 is open at the front part thereof and has an extension 14 above the upper edge 15 of the sides or plates 12. The extensions or hinging parts or lugs 14 of the two side plates 12 are in alignment and hinged or pivotally held to the extensions or parts 15 by screws 16 or otherwise are lugs or projections of the foldable keyboard frame 10 member 11. The keyboard member 11 has side portions 17 which are connected by a transversely extending integral bar or rib 18, and at the upper edge thereof curves upwardly to provide one or more parts or feet 15 19. The part or parts 19 are adapted when the member 11 is moved on its hinge or pivot 16 to rest upon the upper edge 15 in the manner shown in Fig. 3, thereby supporting the frame member 11 together with 20 the parts or keys movable therewith in substantially overhanging relation to the platen carriage as will be presently described.

The member 11 has side plates 20 which may form an extension to the sides 17 and 25 which are adapted to extend inward so as to substantially abut against the inner faces of the side plates 12. Extending transversely between the sides 20 are rods 21, 22, 23 and 24. These rods are rigidly held between the sides of the foldable frame member 11 and each rod or bar is adapted to form a support for a set or bank of levers 25 on the outer ends of which are the usual character keys 26. There are three rods for 30 the character or printing keys, the purpose of which is to permit the fulcrums or pivots of the several series or banks of keys to have substantially the same leverage in order that a substantially uniform touch for 35 the operator may be provided. The key-operated levers 25 are each normally forced in one direction by a spring 26*, one end of which is fastened to each key-lever and the other end to a transversely extending 40 45 angular bar or rod 27 mounted between the sides of the foldable member 11.

Each key-lever 25 forms a break joint with an auxiliary lever 28, the latter in effect being a continuation of the key-levers 25 except for the break joint connection which is provided to adapt the frame member 11 with the key-levers 25 to be folded therewith for compactness, and which are so arranged that each key-lever will select 50 55 and immediately and directly engage its own corresponding coöperative auxiliary lever when the member 11 is moved to an unfolded and normal operative position. Each pair of coöperating levers 25 and 28 thus form in effect a two-part key-operated lever. The ends of the levers 28 may have 60 a part or member 29, Figs. 11 to 18, secured thereto by rivets or otherwise. The part 29 is bifurcated to span the outer end 65 of the lever 28 for securing purposes and

is also bifurcated, as at 30, between which bifurcated portion is a roller 31 which is adapted to form an anti-friction bearing surface for the lower edge of its coöperating lever 25 when the said lever is in an operative position. Instead, however, of the construction shown in Figs. 11 to 18, the ends of the lever may be constructed as shown in Figs. 14 to 16, which differ only in that the part 29 instead of being bifurcated for the reception of the key-lever 25 for securing purposes is simply provided with a flange 32 for securing purposes, while in Figs. 17 to 19 the ends of the levers 28 are bent or formed with an integral portion 33. This part 33 has a horizontal part 34 and an upright part 35 separated from the main part of the lever to provide a space for an anti-friction roller 36 against which the key-lever 25 may rest, the space being of sufficient width to retain and guide its coöperating key-lever in proper relation thereto during the normal operation of the machine. The levers 28 are likewise arranged in sets or banks and the different sets of levers 28 are pivotally supported upon transversely extending bars or rods 37, 38 and 39, respectively. The rods or supports 37 to 39 are arranged in parallel relation to the rods 21 to 23 and under the same and so that said levers 28 are supported above the rods 37 to 39, while the key-levers 25 are suspended from their supporting rods. Each of the key-levers 25 as well as the levers 28 are supported on the rods by an integral bearing formed by lugs 40 and 41 which are spaced apart and are connected together by a bar or portion 42, Fig. 8, which serves to provide an extended bearing and which may also serve as a means for properly spacing the levers apart along the several bars or supports. Each lever 28 extends inward and downward and is normally forced in one direction by a spring 43 one end of which is connected at its inner end to the lever 28, and the other end of which spring is held to a transversely extending bar or plate 44. The springs 43 and 26* therefore serve to hold the levers 25 and 28 in normal operative position and to restore them to their normal position when any one of the key-levers is depressed.

At the inner extreme end of each lever 28 is a link 45 one end of which is connected to a key-operated lever 28 and the other end to its coöperating type-bar 46. Each type-bar 46 is pivotally supported at one end, as at 47, in a hanger 48 or other support arranged on the transverse frame plate 13 of the main frame member 10, and the other end of the type-bar 46 is provided with a type head or block 49 on which may be arranged a plurality of type, one for lower case, the other for upper case, and still a third for figures, although for certain pur-

poses and in certain instances only two types may be used if desired in which case the number and arrangement of the key-levers and type-bars may be changed. The type 5 heads may rest on a cushion held to a transverse plate extending between the sides 12 of the main frame member 10. It will be evident, therefore, that as each key-lever is depressed, its motion will be imparted to its 10 coöperating lever 28, and by means of the link 45 will force a type-bar upward and rearward against a platen 50.

A platen carriage 51 is movable lengthwise and transversely of the machine on a 15 bed 52 in which the platen is rotatably mounted. The carriage may have a sliding connection as by a rail 53 along one edge thereof and at the rear edge may have one or more rollers 54 which are adapted to 20 travel along a rail 55 of the carriage bed in the letter-space movement of the carriage, or balls or other anti-friction devices, as well as other means for properly holding the carriage to the carriage bed may be provided 25 as preferred. The carriage bed may be supported at or near its ends by horizontally extending bars 56. These bars 56 are held to vertically movable slides or posts 57 which may be guided at the upper portion thereof 30 in brackets located at the rear corners of the machine frame. The slides or posts may be connected together transversely of the machine by means of rods or otherwise, and at their lower ends may also be connected by 35 a rod, as 58, to properly hold the slides apart and to cause them to move uniformly by the platen shift mechanism.

The platen shift mechanism may be of 40 any suitable kind. As shown, Figs. 1 to 3, and Figs. 9 and 10, there is a lever 59 which is pivoted, at 60, to a transversely extending rod. This lever 59 is normally forced in one direction by a spring 61 and at its outer end may be bifurcated and provided with a roll 45 which is adapted to be engaged by the lower edge 62 of a second lever 63. The two levers 59 and 63 form a substantially two-part lever in order that a break joint may be secured for folding purposes. The levers or 50 parts 59 and 63 are for shifting the platen to a position for printing the upper case characters, the normal position of the platen and carriage being for the lower case characters. The lever or part 63 is pivoted at its 55 inner end to the transversely extending rod 21 and is retained in its normal position by a spring 64, the said spring being attached at one end to the transverse bar 27. At the outer end of the lever 63 is a key or finger piece 65 by which the said lever may be depressed for platen shift purposes. The inner end of the lever or part 59 is enlarged, at 66, and is provided with a slot 67 through 60 which the rod 58 passes and as the lever 59 is moved on its pivot at the depression of

the key 65, the rod 58 will be raised together with the platen carriage and its support. The figure shift and the cap shift are located in close relation to each other on one side of the machine, the said figure shift action being shown best in Fig. 10. This action is also of a two-part character to permit folding. The lever 68 has its outer end provided with a key or finger piece 69 and at its inner end, at 70, is pivotally held and supported 75 by the transverse rod 21 and said lever is held in its normal position by means of a spring 71. The lever or part 68 at its lower edge engages a roller held in a bifurcated end 71 of a shift lever or part 72. The lever 72 80 is held to a transversely extending tubular rod 73 and said lever has its inner end normally forced downward by a spring 74. At the inner end the lever 72 is pivotally held to the transverse rod 58 so that when the 85 said lever is depressed the slides 57 will be forced upward but to a greater extent than when the key 65 is depressed. The depression of the lever 59 also depresses the lever 72, but the latter lever may be operated independently. The connection between the member 72 and the relative action between this lever and the lever 59 of the two platen shift movements and the means whereby the 90 said levers actuate a transverse bar in order that the platen may be positively held at the proper point as each shift lever is depressed, is substantially the same as disclosed in the application of Otto Petermann, Sr. No. 654,758 filed October 14, 1911, and is therefore not shown in detail herein. By the 95 means shown the carriage and platen when in its normal position may be raised and lowered for printing different characters and by constructing the platen shift action as set forth, the members or levers 68 and 63 may be folded with the type-bar operating key-levers when the frame member 11 is moved from its normal position shown in Figs. 1 and 2 to the folded position shown in Fig. 3. 100

An escapement mechanism of any suitable kind is provided whereby the carriage may be moved for letter spacing. This escapement mechanism may be of the type shown in the patent to Frank S. Rose, No. 948,553 115 dated February 8, 1910, or of any other suitable character. The escapement mechanism may consist of the usual rack with dogs mounted upon a rocking carrier or arm which is adapted to be engaged by a rocking 120 member in the form of a tappet which is mounted upon a rocking bar 75. The rocking bar is supported on vertically movable arms 76 or formed integral therewith and said arms are pivotally held to the transversely extending rod 58 so as to rock back and forth thereon and to partake of its vertical shift movement as disclosed in the application or in the patent herein referred to. The arms 76 at their upper ends are 130

slotted and are engaged by the ends of bell-crank levers 77, the latter being operatively connected to the universal bar 78 by arms 79 or otherwise. The universal bar 78 may 5 be of an L-shaped angle iron and is located normally above a projecting finger or tongue 80 on each key-operated lever 28, and said universal bar is supported in the forked ends 81 of spacing levers 82. The spacing 10 levers 82 have downwardly extending lugs 83 adapted to be supported on one of the transverse rods, as the rod 39, and at the other end may be bifurcated and provided with a roll adapted to be engaged by the 15 lower edge of the space bar levers 84. These levers 84 may be suspended and pivotally held, at 85, to the transversely extending rod 24, and at their outer ends are connected by the usual spacing bar 86, the space levers 20 being held in their normal operative position by means of springs 87, one end being attached to said levers and the other end to the angle plate or bar 27. It will be evident that as each key-lever is depressed for printing 25 purposes, the universal bar will also be operated by means of the tongue 80 to operate the escapement mechanism for letter spacing purposes, and the said universal bar is likewise operated independently of the 30 type-bar operating key-levers each time the spacing bar 86 is operated in order that proper spacing may be obtained between words.

In the character of machine shown, a 35 standard or universal keyboard is provided consisting of banks or sets of keys, each key operating an independent type-bar which is forced upward and rearward for printing purposes and said key-board includes also 40 the spacing bar 86 as well as the spacing lever. It will be seen that each of these key-operated parts of the keyboard is pivotally supported on a supplementary or folding member 11 of the frame, and each member 45 has its corresponding lever mounted upon the main member 10 of the frame forming substantially a two-part type-bar key lever action, letter-spacing action, and platen-shift action, all of said parts mounted upon 50 the member 11 being adapted to fold upward and rearward with said frame member 11 in order that the machine may be made compact for transportation and for other purposes and in a way that a minimum number 55 of parts are employed.

The shift levers 63 and 68 are each provided with a downwardly and horizontally extending lip or portion 88 providing above the same a slot 89 either one of which is 60 adapted to be engaged by the lower end of a finger lever 90. The finger lever 90 is pivoted, at 91, to the frame member 11 and is adapted to be shifted for the purpose of locking either shift lever in its depressed

position, and said lever is also provided with 65 a projection, as 92, which is adapted to engage a projection 93 on the shift lever member 68 to lock the same against movement. This feature is not claimed herein.

Suitable alining mechanism for the type-bars may be provided at the printing point, 70 and suitable line spacing mechanism may be employed for moving the platen the proper distance for line-spacing purposes. There may be also provided suitable ribbon mechanism 75 by which the ribbon may be moved both lengthwise and the ribbon vibrated to and from the printing point at each printing operation in order that the writing may be seen immediately after printing, and the 80 said ribbon mechanism may be of such a character that the ribbon may remain inactive to permit stencils to be made or to adapt the ribbon to have a plurality of fields or colors thereon as is common in 85 many types of machines of this kind. In the drawings, the ribbon spools 93 only are shown and these ribbon spools are mounted to rotate independently upon upright posts 94 carried by the arms or bars 56. Each ribbon spool 90 may have a worm gear 95 and this worm gear may be engaged by a worm 96 which is rotated by a ratchet wheel 97, the teeth of which are adapted to be engaged by a pawl 98 carried by and rocking with the 95 bar 75 of the upright arms 76 so that as the said arms 76 are operated and the pawl moved back and forth, each movement will 100 impart a rotary movement to one of the ribbon spools, one of which spools is held fast to move with the worm gear 95 and the other of which is free so that the ribbon may be wound on or unwound from either of the spools according to which spool is positively rotated in the usual manner. The line spacing, 105 ribbon mechanism and certain other features referred to herein may be substantially the same as disclosed in applications filed or patents issued in the name of Otto Petermann.

Figs. 20 to 26 show a machine in which the key action exerts a pull upon the type-bars instead of a push as in the construction already described. The construction also shows the universal bar as located under the key-operated levers instead of above the same and further shows a modified form of platen shift mechanism. As in the other construction there is a break in the key action and instead of the foldable parts or 110 members of the key action being supported from different transversely extending rods, all of such levers or parts are supported from a single rod, the bearings being arranged about the rod so that they will not 115 interfere during the printing or other action.

Each lever 99 has on its outer end a key

or finger 100 and said lever is pivotally held at its inner end to a transversely extending rod 101. The levers 99 are provided with an integral bearing consisting of lugs spaced 5 apart and tied together by a rod or bar and as in the other form may be utilized to space the levers properly apart along said rod. Each key-lever 99 is held in its normal position by a spring 102 and the lower edge of 10 each lever is adapted in its normal working position to rest against a roller carried by a bracket or extension 103 secured to or formed as a part of a lever 104. The lever 104 forms one part of each key action and is 15 suspended on a transverse rod 105 which is carried upon the main frame member 106, the transverse rod 101 being mounted upon the foldable member 107 of the frame. The lever 104 is held in its normal position so 20 as to be engaged by its coöperating lever 99 by a spring 108. A link 109 connects each lever 104 to a lug or projection 109* extending rearward from each type-bar so that as each key 100 is operated, the lever 25 104 will have its inner end forced downward and through the link 109 will force the type-bar to printing position, there being a comb plate 110 to guide the inner end of each lever 104. The several banks of 30 keys of the key action are similarly constructed and the same reference numerals are therefore applied, the difference being that the distances between the brackets 103 and the pivot points of the levers 99 of 35 the several sets vary in order that the touch with the several key actions will be substantially the same. The space levers 111 are also supported upon the transverse rod 101 and are connected together by a space 40 bar 112 and said levers 111 act upon the space levers 113 in substantially the same manner as in the key action for printing purposes. The levers 113 have downwardly extending slotted guide portions 114 for the 45 universal bar 115 so as to exert a downward thrust thereon instead of upward, said universal bar being connected to bell-crank levers in substantially the same manner as already described, except that in this case 50 the horizontal arms of the bell-crank levers extend rearwardly instead of forwardly as in the other construction.

In the platen shift movement of the construction of machine shown in Figs. 20 to 55 26 and shown in detail in Figs. 25 and 26, the operation is somewhat similar to that shown in Figs. 9 and 10. For printing capitals or upper case characters, the lever 116 is pivotally held at 117 to a transversely 60 extending rod and is connected directly to the vertical posts or slides by which the carriage is elevated as already described, and at the outer end of said lever is a roller 118 which is engaged by the lower edge of a shift lever 119. The shift lever 119 is also 65 pivoted to the transverse rod 101 and at its outer end is provided with an operating key 120 and is held in its normal position by a spring 121. As the key 120 is depressed a like movement will be imparted to 70 the outer end of the lever 116 so that the inner end of the lever 116 will be forced upward carrying with it the platen and carriage. The shift mechanism for figures and like characters shown in Fig. 26 is substantially the same except that a different throw is provided to place the platen and carriage in a relatively different position with respect to type on the type-bars. The lever 122 is held at 123 to a transverse bar and is 75 likewise connected directly to the posts for shifting the carriage and platen, and its outer end has an anti-friction connection with the lower edge of a shift lever 124. The lever 124 is pivoted to the transverse 80 rod 101 and is held in its normal position by a spring 125, the outer end of said lever being provided with a finger key or part 126. Each of the levers 116 and 122 is provided with a projection 127 of relatively 85 different distances from the pivots of said levers. The projection 127 of the lever 116 is adapted to engage a screw 128 held to a bracket on the main member 106 of the machine frame and therefore limits the 90 throw of said lever 116. A shorter adjustable stop or screw 129 is also held in the bracket and is adapted to engage the projection 127 on the lever 122 when the latter is operated. This will permit a greater 95 throw owing to the stop 129 being relatively shorter than the stop 128, thus the platen may be given different movements to adapt figures and other characters to be printed. The entire member 107 with the 100 keys and a part of the action including the type-bar key-levers, the spacing key-levers and platen shift levers mounted upon the frame 107 are adapted to be folded upwardly and rearwardly therewith to make 105 110 the machine compact as already explained.

It will be understood that the machine herein described is adapted to be packed in a special case for carrying or storage purposes and which case also serves as a means 115 to keep the machine free from dust. The carrying case may be of such a character that the machine may remain therein when in use or may be removed from the case as preferred.

From the foregoing, it will be seen that simple means is provided whereby a type-writing machine of the visible kind may be folded so as to make the same more compact than when in use; that effective means 120 125 is provided whereby a standard keyboard may be employed and at the same time permit the parts to be properly operated when

the machine is in an unfolded position; and that simple means is provided whereby the various parts of the typewriting machine may be operated from the keyboard in a manner similar to the ordinary visible writing machine.

Having thus described our invention, we claim as new and desire to secure by Letters Patent:—

- 10 1. In a typewriting machine, the combination of a main frame, a foldable frame member pivotally held to the main frame at the upper portion thereof and foldable upwardly and rearwardly to make the machine 15 compact when not in use, key-operated levers pivotally held to different supports in the foldable member and foldable upwardly and rearwardly therewith, said levers having parts arranged in alinement transversely 20 of the machine in the same horizontal plane and carrying keys arranged in banks, a series of horizontally arranged levers having parts thereof located below the key-operated levers and directly engaged by said 25 25 transversely and horizontally alined parts of the key-operated levers, said horizontally arranged levers being pivotally held to the main frame on different transversely extending supports arranged in the same 30 horizontal plane, and type bars supported on the main frame and operatively connected with said horizontally arranged levers.
2. In a visible typewriting machine, a main frame member, a foldable frame member pivotally held to the main frame member and provided with means adapted to engage the upper portion of the main frame member and be supported thereby when the 40 said frame member is moved to a folded position over and above the main frame member, and a standard keyboard mounted to fold with the foldable frame member.
3. In a typewriting machine, a main frame member, a foldable frame member pivotally held to the main frame member and provided with feet adapted to engage the upper portion of the main frame when the said frame member is moved to a folded 50 position over and above the main frame member, and a standard keyboard mounted to fold with the main frame member.
4. In a visible typewriting machine, a main frame member, a foldable frame member pivotally held to the main frame member and provided with feet at opposite sides thereof adapted to engage the upper edge of the main frame member when the said frame member is moved to a folded position over and above the main frame member, and a standard keyboard mounted to fold with the main frame member.
5. In a typewriting machine, the combination of a platen carriage, a support

therefor, a plurality of upwardly and rearwardly striking type-bars, a link for each type-bar, a plurality of levers one for each link and type-bar arranged in banks or sets to provide fulcrums of relatively different distances from the point of connection with the links, a plurality of key-levers having a break joint connection with the first-mentioned levers and corresponding in number therewith and suspended also in banks or sets, a frame member forming a support for the first-mentioned levers, a frame member pivotally held to the main frame member and forming a support for the key-levers and adapted to be folded upward and rearward with the key-levers for the purpose of making the machine compact and to place said key-levers out of operative relation with the first-mentioned levers, and spacing and shift levers also mounted upon the foldable member of the frame and having a break connection with other levers on the main member of the frame and foldable with the key-levers and combining with the key-levers to make a standard keyboard.

6. In a typewriting machine, the combination of a platen carriage, a support therefor, a plurality of type-bars, a link for each type-bar, a plurality of levers one for each link and type-bar arranged in sets to provide fulcrums of relatively different distances from the point of connection with the links, a plurality of key-levers forming a part of a standard keyboard and having a break joint connection with the first-mentioned levers and corresponding in number therewith and suspended in banks, a frame member forming a support for the first-mentioned levers, a frame member pivotally held to the main frame member and forming a support for the key-levers and adapted to be folded upward and rearward with the key-levers for the purpose of making the machine compact and to place the key-levers out of operative relation with the first-mentioned levers.

7. In a typewriting machine, the combination of a platen carriage, a support therefor, a plurality of upwardly and rearwardly striking type-bars, a plurality of horizontally arranged levers one for each type-bar and operatively connected therewith and arranged in banks to provide fulcrums of relatively different distances from the point of connection with the type-bars, a plurality of horizontally arranged key-levers having a break joint connection with the first-mentioned levers and corresponding in number therewith and also arranged in banks, foldable means forming a support for the key-levers to adapt said key-levers to be moved into overhanging relation to the type-bars, and spacing and shift levers also mounted upon the foldable member of the frame and

having a break connection with other levers and foldable with the key-levers and combining with the key-levers to make a standard keyboard.

5. In a typewriting machine, the combination of a platen carriage, a plurality of pivotally held and substantially horizontally arranged type-bars, pivotally held levers connected to the type-bars and extending 10 horizontally substantially parallel with the normal position of the type-bars and under the same, a plurality of pivotally held key-levers having their entire body portion extending substantially horizontally and having 15 their inner portion interposed between the type-bars and the first mentioned levers and directly over said latter levers and forming a break-joint connection therewith, a main frame member forming a support 20 for the first mentioned levers, and a frame member forming a support for the key-levers and pivotally held to the main frame member at a point to swing the key-levers substantially horizontally away from the 25 first-mentioned levers and break the connection therewith and move the levers upwardly and rearwardly over the main frame member to a more compact position.
9. In a typewriting machine, the combination 30 of a platen carriage, a plurality of pivotally held type-bars pivotally held levers connected to the type-bars and extending substantially horizontally, a plurality of pivotally held key-levers having 35 their entire body portion extending substantially horizontally and having their inner portion interposed between the type-bars and the first-mentioned levers and directly over said latter levers and forming a break- 40 joint connection therewith, a main frame member forming a support for the first-mentioned levers, and a frame member forming a support for the key-levers and pivotally held to the main frame member to 45 move the key-levers away from the first-mentioned levers to a more compact position.

10. In a typewriting machine, the combination of a platen carriage, a plurality of 50 type-bars having a substantially horizontal normal position, a plurality of substantially horizontally arranged levers located under the type-bars, and a plurality of substantially horizontally arranged key-levers 55 forming a part of a standard keyboard and arranged in banks and having a part thereof interposed between the type-bars and the first-mentioned levers, said key-levers having a break-joint connection with said first- 60 mentioned levers and movable from a normal operative position to a more compact one.

11. In a typewriting machine, the combination of a platen carriage, type bars, hori-

zontally arranged levers located under the 65 type bars and operatively connected to actuate said type bars, a keyboard support foldable relatively to said levers and type bars from a normal operative position to a more compact inoperative position, and horizontally arranged key-levers mounted on said support to fold therewith, the inner ends of said key-levers directly engaging the levers located under the type-bars when the keyboard support is in normal position and 70 having a break joint connection with said levers.

12. In a typewriting machine, the combination of a platen carriage, and two-part 80 substantially horizontally arranged platen shift levers having a portion of one part located over a portion of the other part and forming a part of a standard keyboard and foldable toward the platen carriage from a normal operative position to a more compact 85 part one.

13. In a typewriting machine, the combination of a platen carriage, and two-part 90 substantially horizontally arranged shift levers having a portion of one part overhanging the other part and movable from a normal operative position to a more compact one.

14. In a typewriting machine, the combination of a platen carriage, escapement 95 mechanism, a universal bar, and two part relatively foldable substantially horizontally arranged spacing levers having one part overhanging the other part and arranged in substantially parallel relation. 100

15. In a visible typewriting machine, the combination of a platen carriage, a plurality 105 of upwardly and rearwardly striking type-bars, a link for each type-bar, a plurality of levers one for each link and type-bar arranged in banks and having fulcrums of relatively different distances from the point of connection with the links, a plurality of key-levers having a break joint connection with the first-mentioned levers 110 and corresponding in number therewith and suspended in banks, a frame member forming a support for the first-mentioned levers, and a frame member pivotally held to the main frame member and forming a support 115 for the key-levers and adapted to be folded upward and rearward with the key-levers for the purpose of making the machine compact and to place the key-levers out of operative relation with the first-mentioned 120 levers.

16. In a visible typewriting machine, the combination of a platen carriage, a plurality of upwardly and rearwardly striking type-bars, a plurality of levers operatively connected to the type-bars one for each type-bar, said levers being arranged in banks, a plurality of horizontally arranged key-le- 125

vers having a break joint connection with the first-mentioned levers and corresponding in number therewith, said key-levers being suspended in banks and foldable with respect to the first-mentioned levers, and foldable spacing and shift levers having a break connection with other levers and combining with the key-levers to make a standard keyboard.

10 17. In a typewriting machine, the combination of a platen carriage, a support therefore, a plurality of horizontally arranged type-bars, horizontally arranged levers connected therewith and arranged in sets with

15 different fulcrums for each set, horizontally arranged suspended levers having a break joint connection with the first-mentioned levers and forming a part of a standard keyboard, said suspended levers being arranged 20 in sets and having different fulcrums for each set, and means whereby the last-mentioned levers may be moved out of coöperative relation to the first-mentioned levers.

18. In a typewriting machine, the combination of a main frame, a platen carriage, type bars supported on the main frame, a plurality of levers supported on the main frame and operatively connected with the type bars, a keyboard support held to the 30 main frame and movable from a normal operative position to a more compact position, and a plurality of groups of levers carrying keys arranged in banks, the groups of key levers being pivotally held at their inner 35 ends to the keyboard support at different distances from the rear end of the support and being movable with the support to compact position, all of said key levers engaging the type bar operating levers at points 40 in alinement transversely of the frame and having a break joint connection with said levers.

19. In a typewriting machine, the combination of a main frame, a platen carriage, type bars supported on the main frame, a plurality of levers supported on the main frame and operatively connected with the type bars, a keyboard support pivotally held to the main frame and foldable upwardly 50 and rearwardly from a normal operative position to a more compact position, and a plurality of groups of levers carrying keys arranged in banks, the groups of key levers being pivotally held at their inner ends to 55 the keyboard support at different distances from the rear end of said support and being movable with the support to compact position, all of said key levers engaging the type bar operating levers at points in alinement 60 transversely of the frame and having a break joint connection with said levers.

20. In a typewriting machine, the combination of a main frame, a platen carriage, type bars supported on the main frame, a

plurality of levers pivotally supported in 65 the main frame and operatively connected to the type bars, a keyboard support held to the main frame and movable from a normal operative position to a more compact position, and a plurality of groups of levers 70 mounted on said support and movable therewith to compact position, the levers of each group being of different length and supporting keys arranged in banks, and the levers of each group adapted to engage the type 75 bar operating levers at a different distance from the pivotal points of said type bar operating levers.

21. In a typewriting machine, the combination of a main frame, a platen carriage, 80 type bars supported on the main frame, a plurality of levers pivotally supported in the main frame and operatively connected to the type bars, a keyboard support held to the main frame and movable from a normal 85 operative position to a more compact position, and a plurality of groups of levers mounted on said support and movable therewith to compact position, the levers of each group being of different length and supporting keys arranged in banks, and the levers of each group being adapted to engage the type bar operating levers at a different distance from the pivotal points of said type 90 bar operating levers, and at different distances from their own pivotal points.

22. In a typewriting machine, the combination of a main frame, a platen carriage, type bars supported on the main frame, a plurality of levers pivotally supported in 100 the main frame and operatively connected to the type bars, a keyboard support held to the main frame and movable from a normal operative position to a more compact position, and a plurality of groups of levers 105 mounted on said support and movable therewith to compact position, the levers of each group being of different length and supporting keys arranged in banks, and the levers of each group being adapted to engage the type 110 bar operating levers at a different distance from the pivotal points of said type bar operating levers, the points of engagement between all of said levers being in alinement transversely of the frame.

23. In a typewriting machine, the combination of a main frame, a platen carriage, type bars supported on the main frame, a plurality of levers pivotally supported in the main frame and operatively connected to the type bars, a keyboard support held to the main frame and movable from a normal operative position to a more compact position, and a plurality of groups of levers 120 mounted on said support and movable therewith to compact position, the levers of each group being of different length and supporting keys arranged in banks, and the levers of 125

each group being adapted to engage the type bar operating levers at a different distance from the pivotal points of said type bar operating levers, and at different distances from their own pivotal points, the points of engagement between all of said levers being in alinement transversely of the frame.

This specification signed and witnessed this 20th day of February, A. D. 1914.
